Moses Gorham Cook

UNITED STATES PATENT OFFICE.

MOSES GORHAM COOK, OF LYNN, MASSACHUSETTS.

PENCIL-SHARPENER.

SPECIFICATION forming part of Letters Patent No. 653,286, dated July 10, 1900.

Application filed August 25, 1899. Serial No. 728,501. (No model.)

To all whom it may concern:

Be it known that I, MOSES GORHAM COOK, of Lynn, in the county of Essex and State of Massachusetts, have invented certain new and useful Improvements in Pencil-Sharpener, of which the following is a specification.

My invention relates to a machine for sharpening lead-pencils; and it consists in a mechanism for holding and rotating the pencil adapted to act in combination with a controllable slide having upon it a mechanism for cutting the wood of the pencil and a rotating grinding-wheel.

15 This machine is illustrated in the accompanying drawings, in which—

Figure 1 is a plan showing all of the parts of the machine. Fig. 2 is a vertical section of the same taken on line 2 2 of Fig. 1.

20 The device for holding and rotating the pencil A consists of a clamp B, mounted upon a hollow shaft C, the said shaft and clamp being made to rotate by a gear D. Rotation is given to the clamp B and its contained pencil A by the crank Q, acting through the shaft F and gears E and D.

The cutting-tool consists of a knife K, adjustably attached to conical casing mounted upon the standard H. This casing has an 30 opening at I, through which the end of the pencil can enter, as shown in Fig. 1, and come in contact with the edge of the knife K. As the pencil rotates the knife K removes the wood and the shavings escape through the opening J.

35 A grinding-wheel L is mounted upon a suitable standard, as shown, and is caused to rotate by a long pinion N, said pinion being driven by the gear O on the shaft F.

The above-described cutting-tool and the 40 grinding-wheel are mounted upon a sliding carriage G, which moves in ways or guides M M' and is limited in its motion by the pins P P'.

To use my machine, I proceed as follows: The sliding carriage G is drawn back, as 45 shown in Fig. 1, and the pencil A is inserted in the clamp B, the end (to be sharpened) of the pencil just entering the casing at I. Now the operator grasps the sliding carriage G with the thumb and finger of his left hand 50 and the crank Q with his right hand. By turning the crank and at the same time sliding the carriage G toward the pencil, which is now rapidly rotating, the wood will be cut away and the grinding-wheel L act upon the 55 carbon and grind it away to the desired point. When this is accomplished, the carriage G may be withdrawn by the fingers of the operator and the pencil taken out.

I claim—

In a pencil-sharpener, a rotating pencil-clamp, a sliding carriage adapted to be controlled by the operator and having mounted upon it a wood-cutting device and a rotating grinding-wheel, mechanism for rotating the 60 pencil-clamp and grinding-wheel, including a spur-gear, said wheel having a long pinion engaging the spur-gear whereby the sliding movement of the carriage does not detach it from the rotating mechanism, substantially 65 as and for the purpose set forth.

In testimony whereof I have affixed my signature in presence of two witnesses.

MOSES GORHAM COOK.
